UNITED STATES PATENT OFFICE

165,423

COMPARTMENTED PLATE

Tony M. Harris, Decatur, Ill.

Application August 13, 1951, Serial No. 16,257

Term of patent 14 years

(Cl. D44—15)

To all whom it may concern:

Be it known that I, Tony M. Harris, residing at Decatur, State of Illinois, have invented a new, original, and ornamental Design for a Compartmented Plate, of which the following is a specification, reference being had to the accompanying drawings, forming a part hereof.

Fig. 1 is a top plan view of a compartmented plate showing my new design.

Fig. 2 is an elevational view thereof, and,

Fig. 3 is a perspective view.

I claim:

The ornamental design for a compartmental plate, as shown.

TONY M. HARRIS.
